UNITED STATES PATENT OFFICE

ANTON BOLLERMANN, OF LOS ANGELES, CALIFORNIA

CASEMENT SASH FRAME

Application filed July 14, 1928. Serial No. 292,712.

My present invention has reference to a construction of frames for casement sashes for a round, elliptical or other arched heads, and my primary object is the provision of a frame of this type that has a pocket in the head thereof for the reception of a box for a spring wound screen and in which the construction is such that the box and screen may be removed from the frame for arranging the screen in the box or removing the same therefrom in an easy and expeditious manner without interfering with the remainder of the frame.

A further object is the provision of a casement sash frame that carries a spring wound screen in the top thereof, so that the screen may be drawn off its roller to fully close the frame when the sash is swung open, and further wherein the frame is grooved to provide the same with water conduits so that rain will be conducted therefrom and the liability of the rotting of the frame thereby is reduced to a minimum.

To the attainment of the foregoing and other objects which will present themselves as the nature of the invention is better understood the improvement resides in certain other novel features of construction, combination and operative association of parts, one satisfactory embodiment of which is disclosed by the accompanying drawings.

In the drawings:

Figure 1 is a face view of my improvement.

Figure 2 is an enlarged sectional view approximately on the line 2—2 of Figure 1.

Figure 3 is a sectional view approximately on the line 3—3 of Figure 2.

Figure 4 is an enlarged detail sectional view approximately on the line 4—4 of Figure 1.

Figure 5 is a fragmentary side elevation of the improvement to illustrate the groove providing the water drip in the edge of the sill.

The side members or jambs of my improved casement sash frame are indicated by the numerals 1, the said side members having their lower ends connected to the sill 2, and the said sill has its outer portion arranged at a downward angle with respect to the sash.

The sill 2 from the ends and for a suitable distance on the top or face thereof, is grooved, as at 3, to provide water drips. The lintel or top strip for the frame is indicated by the numeral 4 and is arranged at a right angle with respect to the parallel sides 1.

The face strip for the frame has its sides 5 attached in the usual manner to the confronting faces of the sides 1 of the frame, the top of these strips being arched or rounded, as at 6. The outer strips 5 snugly receive therebetween the frame 7 of the sash that has a round or arched head. The round or circular head of the strip 5 is grooved or channeled, as at 8, the said channel extending into the parallel sides of the said strip and providing a gutter or water drip.

The inner or abutment strip for the sash 7 comprises a lower fixed section 9 and an upper removable section 10, there being an angle or miter joint between these sections, which permits of the section 10 being readily removed from the sides of the frame. The upper strip sections contact with the lower and straight edges of the circular head stop 11 for the sash 7. This head stop 11 is not fixed to the frame and has its outer straight sides fixed by screws or the like to depending portions on the parallel sides 12 of a metal box 13. The box 13 is received in a pocket 14 formed by strips or plates that are secured to each other and to the upper portion of the arched part 6 of the frame receiving strips 5. The metal box like member 13 is of a greater width than the head stop 11, so that the open lower portion thereof is projected a slight but suitable distance beyond the inner face of the said stop strip 11 and the inner faces of the strips 9 and 10.

The end walls provided by the metal box 13 have fixed thereon suitable bearings for the shafts or trunnions of a spring influenced roller 15 that has wound therearound a mesh or like screen 16. The outer end of the screen has secured thereon a finger piece 17 which is designed to engage with a suitable catch element on the upper face of the transverse strip that is fixed on the sill 2 when the screen is drawn to cover the opening in the frame and when the sash 7 is swung to open position.

The inner portion of the frame is provided with an inner strip 18 which, with the strips 9, 10 and 11, afford a guide for the edges of the mesh or screen 16. The inner strips 18 and the top strip 19 for the sill are provided with grooves 20 for stucco or like plaster and the strip 5, as well as the under face of the sill 2 are provided with like grooves for stucco or other outer facings. The inner face of the frame has attached thereto the usual trim.

It is believed the simplicity of my construction and the advantages thereof will be understood and appreciated by those skilled in the art when the foregoing description has been carefully read in connection with the accompanying drawings. When it is desired to remove the screen and head jamb it is merely necessary to unscrew the stops 9 and 10, open the sash and then remove the screen and head jamb. It will be thus noted that the parts may be easily assembled and as easily disassociated.

Obviously I do not wish to be restricted to the precise details herein set forth and, therefore, hold myself entitled to make such changes therefrom as fairly fall within the scope of what I claim.

Having described the invention, I claim:

A casement window construction comprising lower side sections adapted to be permanently mounted in the frame, upper side sections adapted to be removably mounted in the frame, a head member mounted upon the upper side sections, a box mounted upon the head member and having an opening at its side, a second box of metal housed within the first mentioned box and having an open side registering with the opening in the side of the first mentioned box, the second mentioned box having end walls overlapping the ends of the head member and attached thereto, said end walls closing the ends of the first mentioned box and a roller journaled in the end walls of the second mentioned box and adapted to carry a screen passing through the openings of both boxes.

In testimony whereof I affix my signature.

ANTON BOLLERMANN.
